UNITED STATES PATENT OFFICE

BENJAMIN F. CROW, OF ST. LOUIS, MISSOURI, ASSIGNOR OF ONE-HALF TO
FREDERICK B. BROWNELL, OF SAME PLACE.

CAR-BRAKE.

SPECIFICATION forming part of Letters Patent No. 363,319, dated May 17, 1887.

Application filed August 25, 1886. Serial No. 211,818. (No model.)

To all whom it may concern:

Be it known that I, BENJAMIN F. CROW, a citizen of the United States, residing at the city of St. Louis, in the State of Missouri, have 5 invented a certain new and useful Improvement in Car-Brakes, of which the following is a full, clear, and exact description, reference being had to the accompanying drawings, forming part of this specification, and in which—
10 Figure 1 is a bottom view of the running-gear of a street-car with my improvement applied. Fig. 2 is a side elevation of same. Fig. 3 is an enlarged perspective view of different parts of the brake disconnected. Fig. 4 is a 15 vertical section through one of the brake-shoes, showing the connecting arm or rod in elevation. Fig. 5 is a face or front view. Fig. 6 is a top view. Fig. 7 illustrates a modification of the bracket.

20 My invention relates to certain improvements in brakes intended more particularly for street-cars, but may be used on all cars; and my invention consists in features of novelty, hereinafter fully described, and pointed 25 out in the claims.

Referring to the drawings, A represents the running-gear of a car.

B represents the shoes, bearing against the wheels of the running-gear, as usual. The 30 shoes are provided on their faces with grooves B', that receive the flanges of the wheels, so that a bearing is had over the entire surface of the periphery of each wheel. The two shoes on each side of the car are connected by 35 a lever, C, and arms D, the arms being pivoted at their outer ends at D' to the shoes and at their inner ends at D² to the lever, the arm of one of the shoes being pivoted to the lower end of the lever and the arm of the other shoe being 40 pivoted to the upper end of the lever. Each arm is preferably made in two parts, one of which screws into the other, as shown in Figs. 3, 4, 5, and 6, so that by removing one of the connecting rods or bolts D' D² the arm may be 45 lengthened or shortened to adjust the shoes to or from the wheels.

The lever C of each series of brake-shoes on each side of the car slips over a non-circular end, E', of a rock-shaft, E, the socket 50 in the lever fitting over the end E' being of a

shape corresponding to the end of the shaft upon which it fits. When each lever has been thus placed upon the end of the rock-shaft, it is held in place by a sleeve, F, having a socket corresponding in shape to the end of the shaft 55 upon which it fits. Next to the sleeve F fits a bracket, G, which receives the round end of the shaft E, and by which the shaft is secured to the bottom of the car, so that it is thus allowed to turn freely, as well as being securely 6c held to the car. The sleeve could be dispensed with and the non-circular part of the shaft that receives the lever be made quite short, and the lever would then fit close up against the bracket.

The form of bracket shown in Fig. 3 will spring, permitting the shaft E to move laterally slightly, so that in case one shoe touches a wheel before the other the bracket will spring away from that wheel, bringing the other shoe 70 against the other wheel, and thus the shoes are automatically adjusted to bear with equal pressure against their respective wheels. This form of bracket is for use when it is located between the wheels; but when it is located outside a stiff bracket, like that shown in Fig. 7, 75 would be used.

I have described the method of holding one of the levers or a lever on one side of the car upon the rock-shaft, and the lever on the other 80 side is held in place in the same manner.

Each shoe is suspended from the body of the car by a rod, H, having a crank on its upper end, which fits in a bracket, H', by which it is secured to the car-body, and which has upon 85 its lower end a crank that fits in the perforation or hole B² in the upper end of the shoe. Each shoe is thus suspended and is free to swing to and from the wheels.

When the brakes are to be applied, the shoes 90 on each side of the car are operated simultaneously by turning the shaft E, and as a means for turning the shaft, I have shown it provided with cranks or arms I, to which are connected rods I', extending to opposite ends 95 of the car, where they are connected in the usual manner to hand shafts or rods J. It will thus be seen that when one of the shafts J is turned to apply the brake, the rock-shaft E will be turned, and the two shoes on each side 100

of the car will be forced from each other and caused to bear against the front and rear wheels, respectively, and at the same time the two shoes on the other side of the car are operated in the same manner. When the brake is released, the shoes are removed from contact with the car-wheels by means of a spring, M, connected to a short arm, M', on the rock-shaft E and to the car-body, as shown in Figs. 1 10 and 2.

In order that the shoes may be held a uniform distance apart and neither of the shoes allowed to get outside of its wheel, I connect them by a tie-rod, U, passing through perforated projections or lugs U^2 cast upon the shoes; there being two nuts, U^3 , on each end of the rod, one on each side of the shoe, (see dotted lines, Fig. 2,) and thus the shoes are

held the proper distance apart with relation to each other.

20

I claim as my invention—

The combination, with the four wheels of a car, of the brake-shoes, hangers suspending each independently of the other, the rods connecting the shoes upon opposite sides of the car in pairs, and separate mechanism on each side of the car for forcing the shoes against the wheels, said mechanism being situated between the wheels in the planes of the wheel-treads, substantially as and for the purpose set forth.

25

BENJAMIN F. CROW.

In presence of—

GEO. H. KNIGHT,
EDW. S. KNIGHT.
